GAME DEVICE

Walter R. Price, Minneapolis, Minn.

Application October 6, 1938, Serial No. 233,599

11 Claims. (CL 273—95)

My invention relates to game devices and contemplates the provision of a reboundable projectile consisting of a ball-like body of resilient material equipped with a vacuum cup adapted to grip a surface against which the projectile is impinged with sufficient accuracy and force to collapse the cup and exhaust the atmosphere from the space between cup and surface. With said vacuum cup thus caused to grip the surface of a stationary or relatively heavy object, the projectile will be deprived of rebounding movement and held in place upon such object, but with the vacuum cup thus caused to grip the surface of a movable object, relatively light in weight, the projectile will rebound and carry the movable object with it.

A feature of the invention resides in providing a projectile of the present nature equipped with a plurality of vacuum cups functioning severally to grip an object.

An object of the invention is to provide simple, durable and inexpensive means of the nature above indicated for the amusement of participants and spectators in playing different games under rules of varying requirements.

With the foregoing and other objects in view, which will appear in the following description, the invention resides in the novel combination and arrangement of parts and in the details of construction hereinafter described and claimed.

In the accompanying drawing, Figs. 1, 2 and 3 illustrate various forms of projectiles embodying my invention, Fig. 1 being a central sectional view of a projectile in one form, Fig. 2 being a similar view of a projectile in another form and Fig. 3 being an elevational view of a projectile in a third form; Fig. 4 is a perspective view illustrating a number of movable targets resting upon a horizontally disposed supporting surface, said view further illustrating a number of projectiles in flight, one thereof being shown as directed toward one of the targets supported upon said surface, and others being shown as directed toward said surface proper; and Fig. 5 is a view illustrating a vertically disposed surface together with projectiles in flight in the direction of such surface.

Reference being had to the drawing, it will be seen that my game device, as shown in Fig. 1, comprises a projectile consisting of a ball-like body 10 of hollow, spherical formation. This body, formed of rubber or other suitable material to render the projectile reboundable, has a vacuum cup 11 incorporated in its structure. The lip 12 of the vacuum cup 11 projects slightly

beyond the spherical surface of said body 10, while the concavity 13 of said cup recedes within the spherical confines of said body.

The projectile shown in Fig. 3, like that shown in Fig. 1, has a spherical body 10 of resilient material and, optionally, may be hollow or solid. Said projectile is equipped with three vacuum cups 11 which may be molded integrally with the body 10 or otherwise suitably affixed thereto.

The projectile illustrated in Fig. 2 is shown as having a solid body 10 in the form of a polyhedron. Said body 10 may be of rubber and molded to form a plurality of vacuum cups 11 exteriorly of said body, as shown.

In the forms of projectiles shown in Figs. 1, 2 and 3, the axes of the cups 11 intersect the centers of their respective projectile bodies 10.

A projectile embodying the features of my invention may be used in various ways to accord with different rules of play. For example, such projectile may be cast toward the floor (Fig. 4) or wall (Fig. 5) with the view of bringing the one vacuum cup, or one of several thereof, into operation upon the impingement of the projectile against floor or wall. This desideratum accomplished, the projectile will become attached to floor or wall, otherwise it will rebound, according to the manner in which it is thrown, to return to the thrower or bounce in another direction to be caught by another player. Obviously, many different rules of play may be devised in which the scoring is based upon the lodgement of the projectile at point of impact against a surface and/or upon the catching of the projectile upon the rebound or otherwise.

The projectile 10^a shown in full lines in Fig. 4, as in flight toward a floor 14 or other stationary horizontal surface, is also indicated in dotted lines as it would appear upon the adhesion thereof to such surface as the result of a successful throw. Another projectile 10^b, shown in full lines in said Fig. 4, as in flight toward the surface 14, is also shown in dotted lines as at the point of impact against said surface, and is again shown in dotted lines as on the rebound, the rebounding of the projectile in such case being due to failure in the effort to present the lip of the vacuum cup 11 squarely against the surface 14 upon impingement of the projectile against the same.

In Fig. 5, projectile 10^c, shown as in flight toward the wall 15 or other vertical surface, is also shown in dotted lines with the vacuum cup 11 gripping such surface and thereby securely implanting the projectile thereon. A second pro-

jectile 10^d, shown in full lines in Fig. 5, as in flight toward the surface 15, is also shown in dotted lines at point of impact against said surface, and again in dotted lines as rebounding therefrom, the rebounding of the projectile in such case being the result of failure of the vacuum cup 11 to grip such surface upon impact of the projectile against the same.

Fig. 4 illustrates a number of portable disc-like targets 16 loosely supported upon the surface 14, said targets being evaluated by numerals, as shown. Also in said Fig. 4, I have shown a projectile 10^e, in full lines directed in flight toward one of said targets. This projectile 10^e is again shown in dotted lines as it would appear upon impingement against such target in such manner as to cause the vacuum cup 11 to grip the target. Further, said projectile 10^e is again shown in dotted lines, as on the rebound and as carrying said target with it. In thus employing a projectile of the present nature together with a movable target, relatively light in weight, a game may be played in which the player seeks to attain predetermined directional flight of the rebounding projectile together with the target attached thereto.

Changes in the specific form of my invention, as herein disclosed, may be made within the scope of what is claimed without departing from the spirit of my invention.

Having described my invention, what I claim as new and desire to protect by Letters Patent is:

1. A reboundable projectile of resilient material comprising a ball-like body provided with a plurality of vacuum cups disposed at the surface thereof with the axes of said cups intersecting said body substantially at the center thereof.

2. A game device comprising a reboundable ball-like projectile having means thereon causing the projectile to adhere, selectively at different portions thereof, to an object impinged thereby, said means consisting of vacuum cups arranged on the projectile about the surface thereof.

3. A game device comprising a projectile consisting of a ball-like body having vacuum cups arranged thereon about its surface and adapted to cause the projectile to adhere at different portions thereof to an object impinged thereby.

4. In combination, a reboundable projectile and a target of sheet material, relatively light in weight, said projectile including a ball-like body and means thereon adapted to cause the projectile to adhere at different portions thereof to a face of the target upon impinging the same and to carry said target with the projectile upon the rebound thereof, said means comprising vacuum cups arranged about the surface of said ball-like body.

5. In combination, a reboundable projectile and a target relatively light in weight, said projectile including a ball-like body of resilient material and means thereon adapted to cause the projectile to adhere to the target upon impinging

the same and to carry said target with the projectile upon the rebound thereof, said means comprising a vacuum cup, the lip thereof extending directly from the surface of said ball-like body.

6. In combination, a reboundable projectile and a target relatively light in weight, said projectile comprising a ball-like body of resilient material having a vacuum cup thereon adapted to cause the projectile to adhere to the target upon impinging the same and to carry said target with the projectile upon the rebound thereof.

7. In combination, a first element consisting of a reboundable projectile comprising a ball-like body of resilient material, and a second element consisting of a target relatively light in weight, one of said elements having a vacuum cup thereon adapted to cause the projectile and target to adhere, one to the other, upon the impingement of the former against the latter, and to cause the target to be carried with the projectile upon the rebound thereof.

8. A game device comprising a projectile consisting of a body having vacuum cups arranged thereon about its surface and adapted to cause the projectile to adhere at different portions thereof to an object impinged thereby, said body providing a backing for the lips of said cups, and the lip of each cup being adapted, under impact against the object impinged by the projectile, to flex back against said body.

9. In a game device, a reboundable projectile including a flexible ball-like body and means thereon adapted to cause the projectile to adhere to an object impinged thereby, said means comprising a vacuum cup, the cup proper being disposed, in part, within the outline of the ball-like body, the lip of said cup projecting directly from the surface of said body, said body providing a backing for said lip, and said lip being adapted, under impact against the object impinged by the projectile, to flex back against the surface of the flexed body.

10. In a game device, a reboundable projectile including a ball-like body of resilient material and means thereon adapted to cause the projectile to adhere to an object impinged thereby, said means comprising a vacuum cup immediately joined to said body, the lip of said cup extending directly from the surface of said body, said body providing a backing for said lip, and said lip being adapted, under impact against the object impinged by the projectile, to flex back against said surface.

11. In a game device, a projectile including a body and means thereon adapted to cause the projectile to adhere to an object impinged thereby, said means comprising a vacuum cup, said body providing a backing for the lip of the cup, and said lip being adapted, under impact against the object impinged by the projectile, to flex back against said body.
